ROTATABLE HONE

Henry Robert Billeter, Highland Park, Ill., assignor to Ammco Tools, Inc., North Chicago, Ill., a corporation of Illinois

Application March 3, 1949, Serial No. 79,394

16 Claims. (CL 51—184.3)

1

This invention relates generally to cylinder hones and it has to do particularly with a tool of this character adapted for honing cylinders of small diameter such, for example, as brake cylinders, piston pin holes and the like.

The structural requirements of a tool of the foregoing character present a difficult problem especially when a plurality of circumferentially-spaced, expansible and retractable abrading members are employed. In tools heretofore devised, the size requirements of the tool, when very small cylinders or faces are to be honed, have limited the tool to a single abrading member with resultant loss in efficiency. Also, such size requirements have heretofore prohibited the use of a tool having plural abrading members in that expansion adjustment would be so limited as not to be practicable.

One of the objects of my invention is to provide an improved tool of the foregoing character which is capable of honing bores as small as $\frac{1}{16}$ " with a high degree of accuracy, which tool is of simple construction, is quite rugged, and is comparatively inexpensive.

Another object is to provide improved abrasive supporting and expanding means for small bore hones whereby small bores may be honed quickly and accurately.

A further object is to provide a small bore hone including a plurality of circumferentially-spaced abrasive carriers which may be expanded and contracted through a greater range of movement than prior tools of this character.

An additional object is to provide a tool of the foregoing character wherein the abrasive carriers are supported in a rigid solid body throughout their entire range of adjustment.

A more specific object is to provide a tool of the foregoing character having a plurality of abrasive carriers supported for expansion and contraction movements, with the inner ends of such carriers disposed in staggered, overlapping relation in their fully contracted condition whereby extent of contraction is increased.

A still more specific object is to provide a tool of the foregoing character having a solid body with circumferentially-spaced, parallel-sided grooves therein for slidably receiving abrasive carriers, said grooves having their inner ends cut away diagonally so that they may project inwardly in overlapping relation with respect to each other without intersection, which grooves have their deeper sides disposed forwardly of the tool radius with respect to rotation to receive complementary-shaped abrasive carriers.

Another object is to provide a tool of the foregoing character wherein an expander element is located in each carrier-receiving groove at the deeper side thereof, each which expander element and carrier constitute a unit substantially filling

2

the groove in the contracted condition of the tool thereby providing compactness with a greater range of expansion.

Still another object is to provide improved means for adjusting a tool of the foregoing character, and particularly adjusting means adapted to be actuated by manual or other power means as the honing operation progresses, such, for example, as employed in various types of honing machines. A further object is to provide carrier adjustment means for a tool of the foregoing character and wherein the adjusting pressure is applied through spring means set to give way and relieve excessive expanding pressure when a predetermined expanding pressure is applied, thereby preventing the application of excessive abrading pressure to the work.

Other objects are to provide an improved carrier mounting whereby the carrier is retained and contracted in an improved manner conducive to a small size tool; to provide for longer tool life in a small bore device of the foregoing character; to provide a device which may be contracted to a very small diameter and expanded to a comparatively large diameter for honing a large range of sizes of small bores; to provide for longer abrasive life in a tool of the foregoing character with faster honing operation; and to provide a tool of the foregoing character which may accurately be adjusted for honing with precision.

Other objects and advantages will become apparent from the following description taken in conjunction with the appended drawings wherein:

Fig. 1 is a side elevational view of one form of "push-type" hone embodying my invention;

Fig. 22 is a cross-sectional view taken along the line 22—22 of Fig. 17.

Referring to the drawings, the "push-type" hone illustrated in Fig. 1 is provided with an adapter head 25 adapted to be supported in a machine, for example a honing machine (not shown), for rotatively driving the tool. A tubular drive shank 26 is rigidly secured to the adapter head 25 in axial alignment therewith and slidably supports an external centering cone 27 for movement therealong. The outer end of the drive shank 26 has an internal thread 28 (Fig. 2) which threadedly receives one end 29a of a body member 29, the other end of which has a reduced portion 30 on which is secured a circular end-plate 31.

The body member 29 serves as a support for the abrading means. It is generally of a cylindrical shape and, preferably, is formed from metal for maximum strength and rigidity. Specifically, body member 29 has three longitudinally disposed channel-like guide slots 32 (Fig. 5) equally and circumferentially spaced in the body member with oppositely disposed side walls 33 and 34 of each guide slot 32 being ranged parallel to and equally spaced on opposite sides of an axial plane passed through the body member. An important feature of my invention resides in the specific arrangement of the side walls 33, 34 and a bottom wall 35 of each of the guide slots 32. In this respect, it will be noted (Fig. 5) that the side wall 33 has a greater depth internally of body member 29 than that of the side wall 34 and that these side walls are joined by the diagonally disposed bottom wall so that the inner ends of the slots 32 are in effect disposed in staggered overlapping relation. Each of the deeper side walls 33 is arranged in advance relation to or forwardly of the guide slot 32 when the tool is rotated in counterclockwise fashion (Fig. 5) about the axis of the body member 29 so that the least deep side wall 34 for each of the guide slots 32 constitutes the trailing wall of the guide slot when the tool is so rotated. This relative arrangement of the walls 33 and 34 is important for the greatest advantages offered by my invention, as will be more fully explained hereinafter. It will be understood that, if rotation of the hone is in the opposite direction (clockwise, Fig. 5), the relative positions of the sides 33 and 34 should be reversed to maintain the deepest side 33 in leading relation to the direction of rotation of the tool. The reasons for the relative arrangement of the sides 33, 34 and the bottom 35 of the guide

slot 32 will become apparent as the description proceeds.

Abrading means is expansively and contractively mounted in each of the guide slots 32 and includes a stone carrier 36 (Figs. 5 and 6) snugly fitting therein while permitting the carrier 36 to be radially expanded and contracted. The bottom or inner edge surface 37 of each of the carriers 36 is inclined at an angle to the side walls of the carrier element to correspond with the angular inclination of the bottom 35 of the guide slot 32 so that the carrier may seat radially inwardly of the channel against the guide slot bottom 35 to allow maximum contraction of the carriers.

An abrading element in the form of an abrasive stone 38 is secured to the top or outer edge of each carrier 36 to form in effect a substantially integral stone-carrier-unit 40 which is retained in the slot 32 against axial displacement in one direction by the end plate 31 and in the other direction by a washer-like plate 41 disposed intermediate the end of the drive shank 26 and an abutment 42 (Fig. 2) formed by the reduced end portion 29a of the body member 29. The plate 41 has radially inwardly directed tongue portions 43 (Fig. 4) shaped and disposed to be freely received in the guide slots 32 and to substantially close each guide slot except for a notch portion 44, the purpose of which will be described hereinafter.

Spring means constantly tends to contract the stone-carrier-units 40 in the slots 32 and is adapted to hold them in contracted relation. This means includes a leaf spring 45 for each of the stone-carrier-units. The springs 45 are distributed circumferentially about the periphery of the body member 29 between each two adjacent stone-carrier-units 40 and each spring has one of its ends received in an opening 46 of rectangular shape in the end plate 31 to prevent angular displacement thereof. The other end of each spring 45 is received in an opening 47 of similar rectangular shape and located in the plate 41, whereby the spring end received in the opening 47 is held against angular displacement. Body member 29 has longitudinal channels 48 (Fig. 5) disposed about its periphery to receive each spring 45 wherein the springs are retained by the plates 31 and 41 in a position radially inwardly of any arc that may be described by the abrasive surface of the stones 38 when the tool is rotated with the stones in their contracted position. Further, the body member 29 is cut away circumferentially to form an annular channel portion 49 (Figs. 2 and 5) in communication with each of the guide slots 32 to allow an arm 51, which is integral with and formed transversely and inwardly from each spring 45, to project into the guide slots 32. The projecting end 51 of the spring 45 is received in a notch portion 52 disposed in the side of the carrier element 36 wherein it rests upon the carrier element and yieldably retains the stone-carrier-units 40 in contracted position in the body member 29. When the stone-carrier-units 40 are radially expanded by means later to be described, the projecting ends 51 cause the springs 45 to be angularly displaced and to continuously urge the stone-carrier-units to their contracted position in opposition to the forces exerted by the expanding means.

Expanding means of the so-called "push-type" is provided for each of the expansible stone-carrier-units 40. It includes a push rod 53 (Fig.

1) which is slidably supported within the drive shank 26 and is removably retained therein by an annular, split spring-ring 54 disposed in frictional engagement with the internal side walls of the drive shank 26. The outer end of the push rod 53 has a pressure button 55 secured thereto and adapted to be engaged by the driving and operating mechanism (not shown) for the tool to advance the push rod internally of the drive shank 26 and to cause an inner end 56 (Fig. 2) of the push rod to move axially outwardly of an enlarged bore portion 57 in the drive shank. A generally cylindrically shaped element 58 (Fig. 2) is slidably supported in the enlarged bore portion 57 and normally has its one end 59 held in contact with the end 56 of the push rod 53 by a compression spring 60 having one of its ends received in an axially disposed opening 61 in the element 58 and its other end engaged with the inner end 29a of the body member 29. Axial alignment of the spring 60 with the body member 29 is maintained by a pilot element 29b integral with the body member 29 and projecting inwardly of the spring. The compression spring 60 not only urges the element 58 into contact with the push rod 53 but also provides the means for restoring the push rod inwardly when pressure is removed from the pressure button 55 so that the tool contractive means above described may be effective to contract the tool.

Actuating means is provided to supply an operative connection between cylindrically-shaped element 58 and the expansible stone-carrier-units 60, whereby when the element 58 is moved axially outward or forward in the bore portion 57 by the push rod 53, the stone-carrier-units will be expanded radially of the body member 29. This actuating means comprises an actuator blade 62 operatively associated with each of the stone-carrier-units 60 and disposed in each guide slot 32 for longitudinal sliding movement thereof along the advance side walls 33. It will be recalled that the plate 41 (Fig. 4) was described as having a notch portion 44 in each of the tongues 43. These notch portions 44 are so proportioned as to allow the actuator blades 62 to freely slide therethrough during the actuating movement of the blades. Each of the actuator blades 62 extends axially inwardly of the bore portion 57 and along channel portions 63 (Figs. 2 and 3) disposed longitudinally of the element 58 to a circumferentially disposed groove 64 in the element 58 where they terminate in hook-like ends 65 serving to lock the actuator blades to the element 58 for movement therewith.

The outer or forward end portion of each actuator blade 62 has two cam portions 66 and 67 disposed with their cam edges in parallel relation on the blade. These cam portions respectively underlie complementary-shaped cam portions 68 and 69 formed in the stone carrier 36 on the side thereof disposed along the advance side wall 33 of the guide slots 32. In other words, the inner forward (with respect to direction of rotation) edge portion of each carrier 36 is provided with a rectangularly shaped notch adapted to receive the expander blade 62, the upper wall of the notch being shaped complementary to the cams 66 and 67 of such blade to provide the cam portions 68 and 69 referred to. In this way the carrier 36 and blade 62 substantially completely fill the slot 32 with the parts free to slide as described, namely, the car-

rier radially and the blade longitudinally. It follows, that any force tending to angularly displace the stone carrier element 36 in a clockwise direction (Fig. 5) will cause the radially innermost portion of the stone carrier element to press the actuator blade 62 against and along the innermost portion of the advance side wall 33. Further, the forces exerted on the respective side walls 34 and 33 of the guide slots 32 will be distributed along a line 70 representing the line of contact of the upper or outer edge of the stone carrier element 36 with the trailing side wall 34 and a line 71 representing the line of contact of the lower or innermost edge 15 of the carrier element along the actuator blade 62, whereby the actuator blade is pressed against the advance side wall 33. Attention is again directed to the relative depth with which the side walls 33 and 34 penetrate inwardly of the body member 29 and by means of which the inclined bottom surface 35 of the guide slot 32 is provided. By allowing the advance side wall 33 to penetrate the body member a maximum distance inwardly, the lines 70 and 71 will be spaced 20 a maximum distance apart. Further, by having the trailing side wall 34 penetrate interiorly of the body member 29 a lesser extent, not only is less material of the body member 29 cut away to form the guide slots but more space is provided in the body members for allowing the advance side walls 33 of the other guide slots in the tool to penetrate further inwardly of the body member. A most important feature of the described arrangement of the side walls of the guide slots 35 32 is the maximum spacing obtained between the described pressure application lines 70 and 71, in a radial direction along axial planes disposed centrally of the slots. It has been found that the greater the spacing between the lines 70 and 40 71 in the direction mentioned, the more rigid and stable support the stone-carrier-units 60 will have during a honing operation. Any slight rocking or angular displacement of the units due to the rubbing action of the stones on the cylinder wall being honed will be in a clockwise direction (Fig. 5), establishing a pivot axis coinciding with the line 70, and the edge coinciding with the line 71 will constitute the swinging edge. If any space exists between the unit and the side wall 50 33 of the slot, the edge represented by the side wall 33 (acting through the blade 62) with less angular movement of the unit than would occur in the case of any portion of the unit removed 55 radially outwardly from the line 71. Therefore the greater the extent the edge represented by the line 71 is disposed radially inwardly from the outer edge of the slot, the greater will be the stability of the unit in the slot. Further, the body member 29 is stronger and the tool can be made with a smaller diameter to accommodate small bores and at the same time will have an increased expansive range with greater rigidity throughout its range of expansion.

65 When using my tool for honing small bores, the tool is connected with any suitable machine, for example a honing machine (not shown) having rotatable drive means and operating means for the tool. The usual controls associated with the honing machine are operated to rotatably drive the tool and to engage the pressure button 55 and move the push rod 53 outwardly of the drive shank 26. Movement of the push rod 53 causes the element 58 to move outwardly in 70 the bore 57 as a result of the direct contact of

the end 56 of the push rod with the end 59 of the element 58. The outwardly directed movement of the element 58 not only compresses the compression spring 60 but also moves each actuator blade 62 axially outwardly whereby the cam portions 66 and 67 on the actuator blades cooperate with the respective cam portions 68 and 69 on the stone carrier element 36 to move each of the stone-carrier-units 40 radially outwardly, while maintaining the relative parallel alignment of the abrading surface of each stone 38 with the axis of the body member 29. The work piece (not shown) containing the bore that is to be honed may be engaged with the hone in contracted condition and the stone-carrier-units 40 are then expanded in the manner just described to contact the surface of the bore and perform the required honing operation while the hone is being rotatably driven.

During the honing operation the tool shown is rotated in a counterclockwise direction (Fig. 5) and the abrasive action of the stones 38 on the wall of the bore will tend to angularly displace each of the stone-carrier-units 40 in a clockwise direction (Fig. 5); but due to the particular arrangement described and the relative proportions of the walls forming the guide slots 32, particularly by having the advance wall 33 extending inwardly of the body member a maximum distance, this tendency towards clockwise displacement is most effectively counteracted to provide maximum rigidity for the stone and carrier assembly.

Assuming that the bore has been completed to the desired size and with the required surface finish, the appropriate controls associated with the honing machine are operated to release the pressure that was previously applied on the pressure button 55. Then, the energy stored in the compression spring 60 causes the element 58 to be moved axially inwardly of the bore 57 and to draw the actuator blades 62 therewith. Further, the movement of the element 58 restores the push rod 53 to its original and normal position. When the actuator blades 62 are moved axially inwardly, the contraction leaf springs 45 cause the stone-carrier-units 40 to move inwardly of their respective supporting guide slots 32 to their contracted position. Likewise, should the actuator blades 62 be partially moved inwardly by partial restoration of the pressure button 55 and the element 58, the leaf springs 45 will cause the stone-carrier-units 40 to be retracted an extent as determined by the relative positions of their cam portions 68 and 69 with the respective cam portions 66 and 67 on the actuator blades 62.

The modified form of "push-type" hone embodying my invention shown in Figs. 8 to 15, inclusive, will now be described. With reference to the hone illustrated in Fig. 8, the tool includes expansible abrasive means and other elements which are similar in construction to certain of the previously described elements found in the "push-type" hone illustrated in Figs. 1 to 7, inclusive. For this reason, like elements in the two tools will be identified by the same reference numerals, except in so far as their respective portions differ one from the other. Specifically, the hone illustrated in Fig. 8 has a push rod 53 (Fig. 10) which is slidably supported in the drive shank 26 and is limited in its sliding movement therein by a pin 75 secured in the side wall of the drive shank with its one end received in an elongated notch portion 76 disposed in one

side of the push rod. A second push rod 77 (Figs. 9 and 10) is located in the drive shank 26 and has one of its ends received for limited sliding movement in an axial bore 78a disposed in the inner end of the push rod 53. The limited sliding movement of the second push rod 77 in the bore 78a is controlled by a pin 79 supported by the push rod 53 and having its free end disposed in a notch portion 80 located in one side of the second push rod 77.

The other end of the push rod 77 has an enlarged head portion 78 (Fig. 9) which projects into the bore 57 and provides an abutment for one end of a pre-loaded compression spring 81 which surrounds the push rod 77. The other end of the spring 81 limits against the inner end of the push rod 53 to hold push rod 77 in outwardly extended and yieldable relation with the push rod 53 to an extent determined by the contact of the pin 79 with the end wall 80a of the notch portion 80. This construction is such that upon movement of the push rod 53 axially outwardly or forwardly of the drive shank 26, the push rod 77 will be carried therewith unless or until the head 78 meets with sufficient resistance to overcome the expansive force of the spring 81, in which event the movement of push rod 53 will be relative to the push rod 77 until the pin 79 contacts the opposite side wall 80b of the notch portion 80.

An operative connecting means is provided between the push rod head 78 and the actuator blades 62, which includes a generally cylindrically-shaped element 82 (Fig. 9) in which is located an axially disposed bore 83, one end of which is closed by a plug element 84 secured in the bore 83 by any suitable fastening means, for example a pin 85. A circumferentially disposed groove 86 is located in close proximity to the other end 87 of the element 82 for receiving the hook-like end portions 65 of the actuator blades 62 for locking these hooked end portions to the element 82. The actuator blades 62 are freely received for movement along channel portions 88 disposed in the end 87 of the element 82. An axially disposed opening 89 is located in the outer end of the element 82 in communication with the bore 83 for freely receiving a push pin 90 which projects outwardly of the element 82 from a circular head portion 91 which is integral therewith. The head portion 91 serves as a seat for one end of a compression spring 92 located in the bore 83, the other end of which is limited against the inner end of the plug element 84. When the tool is at rest and in fully contracted condition, the arrangement and structural characteristics of the parts previously described is such that the outer end of the push pin 90 is held in contact with the inner end 29a of the body member 29 and the wall 76a (Fig. 10) of the notch portion 76 is held in contact with the pin 75 by the pre-loaded condition of the compression spring 81 and the spring 92. It should be mentioned at this time that the spring 81 requires a greater force to effect its further compression than the force required to effect compression of the spring 92. Thus, it can be seen that when the push rod 53 moves inwardly of the drive shank 26 transmission of its movement will be through the spring 81, and the spring 92 will be compressed as a result of the relative compressibility factors of the two springs. This arrangement, including the relative compressibility factors of the two springs 75 81 and 92, limits the expansive pressure applied

to the tool as will become apparent hereinafter in describing the operation of the tool.

The expansible abrasive means provided for the tool illustrated in Fig. 8 is substantially the same and embodies the same inventive concept as that of the tool illustrated in Fig. 1. The expansible abrasive means is altered slightly in that each stone carrier element 93 (Fig. 11) is reduced slightly in transverse width to allow the abrasive stone 38 to bear against the trailing side wall 34 of the guide slots 32. Slightly greater stability and rigidity is provided for the stone-carrier-units 94 with this construction which results from the further spacing apart of the thrust-receiving line 71 with a thrust-receiving line 95 disposed along the outer edge of the trailing wall 34.

Spring means is provided to yieldably retain the stone-carrier-units 94 in their contracted position, which includes a spring 96 (Figs. 11 and 14). The spring 96 is formed of a single piece of spring wire having a pair of looped portions 97 intermediate its ends and angularly displaced one from the other. A hook-like end portion 98 is formed on each end of the spring 96 adapted to enter spaced openings 99 in the body member 28 for fastening the spring to the body member. The angular displacement of the loops 97 one with the other is such that one loop is allowed to enter the notch portion 52 in the stone carrier 93 to yieldably retain the stone-carrier-unit 94 in contracted position while the other loop 97 rests upon the bottom wall of the annular channel portion 49. When a stone-carrier-unit 94 is expanded the spring 96 yields in angular fashion about the spring loop 97 that is resting upon the bottom wall of the channel portion 49; however, the other spring loop 97 remains in the notch 52 to continuously urge the stone-carrier-unit to its fully contracted position in the guide slot 32.

The operation of my "push-type" hone tool shown in Fig. 8 will now be described. Assuming that the work piece (not shown) is engaged with the tool, the machine (not shown) for rotatably driving the tool is started in operation and the controls associated with the machine are operated to engage the pressure button 55 and move the push rod 53 axially outwardly of the drive shank 28. This movement of the push rod 53 is transmitted through the loaded compression spring 81 causing the second push rod 71 to be yieldably moved thereby so that its head portion 73 will move the cylindrically-shaped element 82 axially outwardly and cause the head portion 91 of the push pin 90 to compress the spring 92 as a result of the normally abutted relation of the outer end of the push pin 90 with the inner end 29a of the body member 29. Further, the movement of the element 82 results in each of the actuator blades 62 being moved longitudinally outwardly or forwardly of the guide slots 32, whereby the cam portions 66 and 67 of the actuator blades cam the respective cam portions 68 and 69 of the stone-carrier-units 94 to move the stone-carrier-units radially outwardly of the body member 29 to engage the walls of the bore to be honed. The stone-carrier-units 94 will be held in honing relation with the walls of the bore to be honed so long as sufficient pressure is applied to the pressure button 55 to maintain an abrasive action on the walls of the bore. However, if more pressure is exerted on the pressure button 55 than is required to hold the abrasive stones 38 in contact with the walls of the bore to be honed, it is clear that the element 82 cannot be moved further axially outwardly in the bore 57 and

therefore, the second push rod 71 will yield relative to the movement of the first push rod 53 and the loaded compression spring 81 will be further compressed. Because of the relative compressibility factors of the springs 81 and 92, the additional pressure required to compress the spring 81 will immediately become apparent to the user of the tool and warn him that the abrasive stones 38 are being held in contact with the walls of the bore to be honed with sufficient pressure. In other words, with this arrangement the spring 81 is pre-loaded to effect expansion of the tool there-through and when the desired expanding pressure is exceeded (as when the pre-load pressure of the spring 81 is exceeded), the spring 81 will give way and relieve the pressure so as to maintain a substantially constant pressure on the stones. Upon completion of the honing operation, the controls for the operating means for the tool are restored to remove pressure from the pressure button 55. When this has been done, the loaded compression spring 92 forces push pin 90 outwardly of the opening 89 in the element 82 to force the element 82 axially inwardly of the bore 57 and restore both push rods 71 and 53 to their normal position where the side wall 76a of the notch 76 limits against the pin 75. Further, the movement of the element 82 draws the actuator blades 62 inwardly allowing the springs 96 to move the blade-carrier-units 94 radially inwardly of the channels 32 an extent determined by the relative positions of the cam portions 66 and 67 with their respective abutted cam portions 68 and 69 on the blade-carrier-units.

Still another form of tool embodying my invention is illustrated in Fig. 16. This tool is of the so-called "pull-type." It includes several elements of construction similar to those found in the previously described hones and where similarity exists, the same reference numerals will be used without further description. Specifically, this hone comprises a head member 110 having a common type of bayonet lock connection 111, 112 with a body member 113. The body member 113 has a reduced and threaded portion 113a (Fig. 17) on which is threadedly received an annular jam-nut 114 for clamping a plate 115 against an abutment 113b on the body member 113. The plate 115 has radially inwardly directed tongue portions 115a which are freely received in the guide slots 32 of the body member 113 and prevent relative angular movement between the plate and body member when the jam nut 114 is tightened against the plate. A second reduced portion 113c is disposed along the body member 113 for reasons later to be described, and a third reduced portion 113d is further provided on the body member 113 to form a shoulder-abutment 116 between the surfaces 113c and 113d.

Adjusting means for radially expanding the abrasive means is supported on the reduced portion 113d of the body member 113 and includes a knurled adjusting nut 117 which is maintained in contact with the connection 111, 112 by a compression spring 118 having its one end resting against the shoulder 116 and its other end bearing against the adjusting nut 117 to continuously urge the adjusting nut against the connection 111, 112. The adjusting nut 117 has an internal thread 119 in which is threadedly received an actuator cage 120 for actuating three actuator blades 121. The actuator cage 120 has radially and inwardly directed tongue portions 122 (Fig. 22) which are freely received in the guide slots 32 in the body member 113 to prevent angular displacement of the actuator cage relative to the

body member at all times. Each of the tongue portions 122 has a transverse notch portion 123 (Figs. 17 and 21) in which is received and locked therein a hook-like end 124 on each actuator blade 121.

The expandable abrasive means later described is expanded as a result of movement of the actuator blades 121. However, in the "pull-type" of hone, movement of the actuator blades 121 axially inwardly of the body member 113 is used to expand the abrasive means, whereas in the previously described "push-type" hone expansion was accomplished by movement of the blade actuators axially outwardly of the body member. Each of the actuator blades 121 has two cam portions 125 and 126 which are adapted to cooperate respectively with a pair of cam portions 127 and 128 forming a part of a stone carrier 129 which carrier is similar in all respects to the previously described stone carrier elements 36 and 93, except for a reversal in arrangement of its cam portions 127 and 128. Likewise, the stone-carrier-unit 130 is similar in all respects to the stone-carrier-unit (Fig. 6) except for the previously described reversal of the cam portions 127 and 128.

In the use of the "pull-type" hone, the tool is placed in registration with the bore (not shown) to be honed and the adjusting nut 117 is rotated in a clockwise direction (Fig. 22) to threadedly draw the actuator cage 120 inwardly of the adjusting nut 117 and its tongue portions 122 longitudinally of the channel portions 113f in the body member 113. The actuator blades 121 are drawn axially inwardly by means of their hook-like end portion 124 being locked in the notches 123 of the actuator cage 120 to cause the cam portions 125 and 126 on the actuator blades to cam the blade-carrier-units 130 radially outwardly and into contact with the wall of the bore to be honed. Thereafter, with the units remaining in contact with the wall, continued clockwise adjustment of the adjusting nut 117 (Fig. 22) causes the nut to advance along the threads on the actuator cage 120 and axially outwardly of the body member 113, until an end 117a of the adjusting nut 117 contacts the jam-nut 114, to compress and load the compression spring 118 whereby the abrasive stones 131 are held in contact with the wall of the bore to be honed with a pressure in accordance with the loaded condition of the compression spring 118. During a following honing operation and as the wall of the bore is abraded away, the stone-carrier-units 130 automatically expand radially outwardly to remain in contact with the surface of the bore being honed because of the compressed condition of the spring 118. This movement of the stone-carrier-units 130 in an outward direction is caused by the actuator blades 121 moving axially inwardly of the body member 113 which in turn results in the adjusting nut 117 moving axially inwardly along the reduced portion 113d of the body member until the adjusting nut contacts the connection 111, 112 to arrest further expansion and abrading action of the stones 131 on the wall of the bore being honed. When it is desired to contract the stone-carrier-units 130, the adjusting nut 117 is adjusted in a counterclockwise direction (Fig. 22) to move the actuator cage 120 axially outwardly of the body member 113 which in turn moves the actuator blades 121 outwardly so that the springs 132 are allowed to move the stone-carrier-units 130 radially inwardly of the body member 113 and to their desired contracted position.

The structure embodied in my described hones

allows a plurality of stone-carrier-units to be used in a small bore hone with increased support for the carrier units and greater rigidity of the tool. By cutting the guide slots in the body member of the tool with an inclined bottom wall and by forming the inner end of the stone-carrier-unit complementary therewith, I have not only increased the expandable range of the tool but also, have provided greater rigidity throughout the range of expansion by having the greatest point of depth of the bottom wall of the guide slot forwardly of the direction of rotation of the tool. Further, my yieldable retaining springs for each of the stone-carrier-units are easily removable from their retaining position on the carrier unit to allow a worn unit to be readily replaced without dismantling the hone.

I claim:

1. A honing tool adapted to be rotated in a predetermined direction comprising a body member having a plurality of circumferentially spaced closed-bottom slots each of which is intersected by the tool radius along a line parallel with the slot sides, said slots having similarly arranged generally diagonally disposed bottom walls extending inwardly and forwardly from one side wall thereof with respect to direction of rotation of the tool, abrasive carriers mounted for expansion and contraction in and shaped complementally to said slots, and a separate carrier expanding cam member mounted in each of said slots between and in operative engagement with the carrier and the slot bottom and adjustable longitudinally therein in one direction to expand said carrier and in the opposite direction to permit it to contract.

2. A honing tool adapted to be rotated in a predetermined direction comprising a body member having a plurality of circumferentially spaced, longitudinally-extending closed-bottom slots each of which is intersected by the tool radius along a line parallel with the slot sides, said slots having similarly arranged generally diagonally disposed bottom walls extending inwardly and forwardly from one side wall thereof with respect to direction of rotation of the tool, elongate abrasive carriers mounted for expansion and contraction in, shaped complementally to and substantially filling said slots, a separate carrier expanding blade mounted in and slidably longitudinally of each of said slots between the bottom thereof and the carrier, and expander elements on said carriers and blades having inclined surfaces complemental to each other whereby longitudinal adjustment of each said blade in one direction expands the respectively engaged carrier and adjustment in the opposite direction permits contraction of the respectively engaged carrier.

3. A honing tool adapted to be rotated in a predetermined direction comprising a body member having a plurality of circumferentially spaced closed-bottom slots each of which is intersected by the tool radius along a line parallel with the slot sides, said slots having similarly arranged generally diagonally disposed bottom walls extending inwardly and forwardly from one side wall of each said slot past said tool radius with respect to direction of rotation of the tool, abrasive carriers mounted for expansion and contraction in and shaped complementally to said slots, the forward edge of each said carrier having a rectangularly shaped notch, expanding cam elements on one wall of each said notch and an elongate carrier expanding

blade mounted in each of said slots within said carrier notch and bearing against said bottom wall and having expanding cam elements complementary to and engageable with the first mentioned cam elements, the arrangement of the cam elements being such that simultaneous adjustment of all said blades in one direction simultaneously expands all said carriers.

4. A head for a small bore hone adapted to be rotated in a predetermined direction comprising a body member having a plurality of longitudinally-extending circumferentially spaced closed-bottom slots, each of which is intersected by the head radius along a line parallel with the slot sides, said slots having similarly arranged generally diagonally disposed bottom walls extending inwardly and forwardly from one side wall of each said slot beyond said head radius with respect to direction of rotation of the head, and a carrier-expander unit mounted in each of said slots for expansion and contraction therein, shaped complementally thereto and substantially filling it, each said unit including a carrier having side and bottom walls shaped similarly to the corresponding slot walls except for a rectangularly-shaped notch in the inner forward part of the longer or leading unit side wall, an expander blade snugly and slidably fitted in each said notch and seated against the bottom wall of the slot to complete the complementary shape of the unit with respect to the slot, and complementary engaged expander elements on each said carrier and blade within the confines of said unit and adapted to expand said carrier as said blade is moved longitudinally in one direction.

5. A small bore honing tool of the character described adapted to be rotated in a predetermined direction, which comprises a cylindrical body member having a longitudinally-extending closed-bottom slot with parallel side walls and intersected in parallel relation to said side walls by the tool radius, the one of said side walls located forwardly of the tool radius, with respect to direction of rotation of the tool, being substantially deeper than the other or trailing side wall providing a slot bottom wall inclined throughout its major portion inwardly and forwardly with respect to direction of rotation and having a portion normal to said one side wall, said slot extending radially inwardly to an extent whereby the mid-point of said bottom wall is short of the center of the body, an abrasive carrier shaped substantially complementary to and snugly slidable in expanding and contracting directions within said slot and having a notch at the lower edge of said deeper side wall equal in width to said normally extending bottom wall portion, a thin carrier expander blade mounted in and slidable longitudinally of said slot within the boundary of the walls of said slot in bearing relation between said slot bottom and said carrier, and inclined complementary expander cam surfaces on each said carrier and expander blade and effective to expand said carrier as said blade is moved longitudinally in one direction and to permit contraction of said carrier when moved in the other direction.

6. A honing tool of the character described adapted to be rotated in a predetermined direction, which comprises a body member provided with a plurality of circumferentially-spaced, longitudinally-extending closed-bottom slots each of which is intersected by a tool radius, the side walls

of each said slot being parallel with the radius line of the respective slot with the side wall disposed forwardly with respect to the direction of rotation extending inwardly a greater distance than the other side wall, each said slot having a bottom wall surface inclined inwardly and forwardly from the shallower side wall to a point forward of the intersecting radius line, so that the bottom walls of all said slots are disposed in staggered, overlapping relation to avoid interference with each other, abrasive carriers mounted in said slots respectively, and carrier expanding cam elements mounted within said slots respectively in bearing relation to the carrier and the slot bottom and movable longitudinally thereof to expand and enable contraction of said carriers, said expanding elements being disposed in nested relation to said carriers respectively so that said carrier and expanding elements in contracted condition are of substantially the cross-sectional shape of said slots which are filled thereby, said expanding elements having portions adapted for connection with actuating means for moving the expanding elements longitudinally.

7. A hone adapted to be rotated in a predetermined direction including a body member having a plurality of longitudinally extending radial guide slots disposed therein, said guide slots each having a longitudinal side wall disposed parallel with and on each of the opposite sides of an axial plane passed through said body member, one of said longitudinal side walls of each of said guide slots being disposed in advance relation in respect to the direction of rotation of said hone and extending inwardly of said body member a greater extent than the other said longitudinal side wall, each slot thereby having a relatively deep side and a relatively shallow side and the bottom walls of said slots being thereby inclined and in staggered, overlapping relation, a stone-carrier-unit disposed in each of said guide slots for radial movement therein and having a bottom surface inclined generally complementary to the bottom wall of the slot, an expander element located substantially within each of said guide slots adjacent the deeper side thereof and operatively connected to said stone-carrier-unit to radially expand said unit, and a separate torsion spring for each of said units supported on said body member and having at least a portion engaging the corresponding unit to urge said unit radially inwardly of said body member and said guide slot.

8. Structure of the class described for honing small bores which comprises a head member having an enlarged body portion with a reduced axial extension, said head member having a plurality of circumferentially spaced slots extending throughout said enlarged body portion and extension, abrasive carriers mounted in said slots within said body portion, end plates at the opposite ends of said body portion for retaining said abrasive carriers longitudinally therein, the inner of said end plates having openings aligned with said slots, an expander blade mounted in each of said slots and including an expander part disposed in the slot of said body portion and an actuating part projecting therefrom through the respective opening in said inner end plate, a hollow drive shank connected to said reduced head portion, confining said inner end plate and enclosing the actuating part of said expander blade, means in said drive shank connected with the actuating parts of said blades therein and adjustable longitudinally of said drive shank for simultaneously moving all said blades to expand

said abrasive carriers, and first spring means in said drive shank adapted to be compressed as said expanding means is moved in expanding direction and tending constantly to move said expanding means in the opposite direction to permit contraction of the tool, and second spring means connected to said head and engaged with each of said abrasive carriers for moving them in contracting direction when said first spring means is effective to move said expanding means in contracting direction.

9. A small bore honing tool comprising a body member having an abrasive supporting portion and a reduced drive extension, a plurality of circumferentially-spaced slots in said body member extending longitudinally throughout said abrasive supporting portion and said extension, abrasive carriers mounted in said slots, end plates at the opposite ends of the supporting portion of said body member for confining said abrasive carriers against longitudinal displacement, the inner of said plates having openings aligned with said slots, an expander blade in each of said slots having an enlarged head part located between said end plates and adapted to expandingly engage said abrasive carrier, and a reduced stem part projecting through and beyond the respective plate opening, a hollow drive shaft secured to said reduced extension and housing the stem portions of said blades, a longitudinally adjustable member in said shaft connected to all said blade stems for simultaneous expansion and contraction movement thereof, a spring in said drive shaft yieldably opposing expansion movement of said adjustable member and adapted to move said adjustable member and blades in contracting direction when said adjustable member is released for that purpose, and spring means connected to said head and engaged with each said abrasive carrier for contracting it when said first spring is effective to contract the tool.

10. A tool of the class described which comprises a honing head, abrasive carriers carried by said head for expansion and contraction movements, means carried by said head for expanding said carriers, means carried by said head for contracting said carriers, a hollow drive shaft for said head, and means for actuating said expanding means including a longitudinally-adjustable member in said drive shaft, a second longitudinally-adjustable member in said drive shaft, a pre-loading spring interengaging and reacting between said first and second members and by which movement of said first member is imparted to said second member, a third longitudinally-adjustable member in said drive shaft connected to said expanding means and actuated by said second member, said pre-loaded spring being adapted to yield and relieve pressure applied through said first and second members when a predetermined pressure is exceeded, and a second spring interengaging and reacting between said third member and a relatively fixed portion of said tool and adapted to be compressed by said third member when it is moved to expand said carriers so as to move said first, second and third members in return direction from expanding position when expansive pressure is released therefrom to enable contraction of said carriers.

11. A rotatable tool of the class described which comprises a honing head, abrasive carriers carried by said head for expansion and contraction movements, means carried by said head for expanding said carriers, means carried by said head for contracting said carriers, a hollow drive

shaft for said head, and means for actuating said expanding means including a pair of longitudinally reciprocable members mounted in said drive shaft, first spring means interposed between said expanding means and a relatively fixed portion of the tool and reacting in axial direction for biasing the expanding means in retracting direction, one of said reciprocable members being operator-controlled during rotation of the tool, and a second, pre-loaded spring interconnecting said reciprocable members so that longitudinal movement of one is transmitted to the other through said spring, said second spring requiring a greater force for compression thereof than the first spring means, said second spring being set to give way at a predetermined pressure to relieve against the application of more than a predetermined expansive pressure.

12. A tool of the class described which comprises a honing head, abrasive carriers carried by said head for expansion and contraction movements, means carried by said head for expanding said carriers, means carried by said head for contracting said carriers, a hollow drive shaft supporting said head, and means for actuating said expanding means including a pair of longitudinally adjustable members mounted in said drive shaft, one of which members is operatively connected to said expanding means, a pre-loaded spring interposed between said members so that longitudinal movement of one is transmitted to the other through said spring, said spring being set to give way at a predetermined pressure to relieve against the application of more than a predetermined expansive pressure and a second spring interposed between one of said adjustable members and a relatively fixed portion of said tool and adapted to be loaded by movement of said adjustable members to expand said carriers in readiness to move said adjustable members in return direction from expanding position upon release of expanding pressure.

13. A tool of the class described which comprises a honing head, abrasive carriers carried by said head for expansion and contraction movements, means carried by said head for expanding said carriers, means carried by said head for contracting said carriers, a hollow drive shaft supporting said head, and means for actuating said expanding means including a first and a second longitudinally adjustable member mounted in said drive shaft, the second member being operatively connected to said expanding means, a pre-loaded spring interconnecting said members so that longitudinal movement of one is transmitted to the other through said spring, said spring being set to give way at a predetermined pressure to relieve against the application of more than a predetermined expansive pressure, means including interengageable stop elements on said first member and said drive shaft for limiting the extent of longitudinal movement of the member relative to the drive shaft for limiting the range of tool expansion, and means including a lost motion connection between said members for limiting movement of said members relative to each other when said predetermined pressure of said pre-loaded spring is exceeded.

14. A tool of the class described which comprises a honing head, abrasive carriers mounted in said head for expansive and contractive movements, longitudinally movable means mounted in said head for expanding said carriers, means mounted in said head for contracting said carriers, a hollow drive shaft connected to said hon-

ing head, and means for actuating said expanding means including a member mounted within said drive shaft for longitudinal reciprocation relative thereto and rotative movement therewith, said actuating means being connected with said expanding means and operative for moving the latter longitudinally, said member having a central axial opening therein, a spring mounted in said axial opening and operatively connected to said honing head and reacting between said honing head and said member, whereby said spring is compressed as said member is moved longitudinally relative to said drive shaft toward said head and is conditioned to move said member and expanding means in return direction from expanding position when expanding pressure is removed from said member.

15. A tool of the class described which comprises a honing head, abrasive carriers mounted in said head for expansive and contractive movements, means mounted in said head for expanding said carriers, means mounted in said head for contracting said carriers, a hollow drive shaft connected to said honing head, and means for actuating said expanding means including a member mounted within said drive shaft for longitudinal movement relative thereto and rotative movement therewith and connected with said expanding means, said member being hollow with its opposite ends substantially closed, a spring mounted within said member, a spring actuator mounted in said member in engagement with the end of said spring adjacent said honing head, said actuator having a part extending through the adjacent end of said member into engagement with said head, whereby said actuator compresses said spring as said member moves in expanding direction to condition said spring to move said member in contracting direction when expanding pressure is removed therefrom.

16. In a honing tool of the type having a hollow drive shaft, a honing head carried by said drive shaft, abrasive-carriers carried by said head for expansion and contraction movements,

and means for expanding and contracting said carriers including an actuating member slideable longitudinally in said head, the improvement which comprises a longitudinally slideable thrust member in said shaft having effective engagement with said actuating member and operative for transmitting thrust to the latter, a longitudinally slideable push member in said shaft, a pre-loaded spring engaging and reacting between said push member and thrust member normally operative for transmitting thrust between the members, said push member and thrust member having lost motion connection enabling relative motion therebetween upon yielding of said preloaded spring, said push member and shaft having interengageable stop elements for limiting the extent of longitudinal movement of the push member relative to the shaft, and means constantly biasing the thrust member and push member longitudinally in the direction away from said head.

HENRY ROBERT BILLETER.
